OF CHICAGO, ILLINOIS, A CORPORATION OF DELAWARE

RAILWAY DRAFT RIGGING

Application filed December 9, 1927, Serial No. 238,752. Renewed December 23, 1929.

This invention relates to improvements in railway draft riggings.

In the operation of railway cars, and more particularly freight cars, a constant source of trouble heretofore has been due to the inability to maintain the standard couplers in their proper horizontal condition or alignment with the deck absorbing device. Heretofore it has been the common practice to key the coupler to the yokes or links at points inwardly of the end sill or buffer block, and substantially the entire support for the coupler has been derived from the usual carry iron located outwardly of the key connection. The standard couplers are extremely heavy and particularly the coupler head or free end thereof, with the result that heretofore the coupler head has had a constant tendency to fall or droop, thus destroying the intended, desired horizontal axial alignment of the coupler shank and shock absorbing device.

The disadvantage above mentioned is accentuated the longer the car is in service, due to the repeated draft and buffing movements in the coupling of cars and in the operation of a train of cars. The overbalanced coupler head continually tends to destroy the usual carry iron; the more the latter is distorted and permits the outer end of the coupler to sag, the greater the other injuries which will necessarily follow to the end sill structure of the car and to the parts of the draft rigging, due to the application of eccentric loads, so that the coupling of the cars together and maintenance of the coupled condition becomes extremely difficult and frequently impossible.

Further, as is well known to those skilled in the art, the normal coupler travel is approximately two and three-fourths inches. At the present time, there is a definite general tendency to increase the coupler travel, particularly in buff, so that the overhang of coupler head in normal full release condition of the rigging, and still more, in full draft condition of the parts, is materially increased with a corresponding damaging effect.

One object of my invention is to provide simple and relatively inexpensive means for

so associating the coupler and draft acting means of the draft rigging that the coupler shank will at all times be maintained in proper axial alignment with the shock absorbing device in all possible positions of the draft rigging from extreme draft to extreme compression, the present invention being primarily concerned with draft riggings employing yoke-acting means of the link type.

Another object of my invention is to provide means for supporting the coupler in such a manner as to prevent any tendency of the coupler to pivot or fulcrum, to thereby prevent drooping or falling of the coupler head and hence to maintain the proper position of the coupler head for effective coupling with adjacent cars.

A still further object of my invention is to provide a combined aligning and draft acting means, such that the coupler may be readily inserted and removed without taking down the other parts of the draft rigging and which means will have the advantages set forth hereinbefore.

More specifically, objects of my invention are to provide a draft rigging having a compression stroke approximating double that of the present standard draft rigging, wherein a novel link arrangement, adapted to be keyed to the coupler shank and having provision forwardly of the key connection for sustaining the coupler head in proper position, is provided whereby the axial alignment of the coupler shank and shock absorbing device is maintained, notwithstanding the greater overhang of the coupler necessitated by the increased travel.

In the drawings forming a part of this specification, Figure 1 is a vertical, longitudinal, sectional view of a portion of a car showing my improvements in connection therewith, the parts being in the position assumed in full release of the shock absorbing device. Figure 2 is a horizontal, sectional view, corresponding substantially to the section line 2-2 of Figure 1, the drawbar, followers, shock absorbing device proper, and links being shown in top plan, however. And Figure 3 is a detailed, sectional view

corresponding to the section line 3—3 of Figure 1.

In said drawings, 10—10 denote the usual center or draft sills of a railway car, preferably of channel section; 11, an angle end sill of the car; 12, end wall sheathing; 13, a floor plate or cover plate for the sills; and 14, a buffer block secured to the angle 11 and end sill member 15, the latter being secured to the center sills 10 by the tie plate 115.

In carrying out my invention, the draft sills 10 are provided with suitable slots to accommodate portions of two reinforcing or cheek plates 16—16 secured to the outer sides 15 of the sills. Each of said plates 16 is provided at the front end thereof with an elongated key-receiving opening 17; intermediate its ends with another elongated key-receiving opening 18; and at the rear with a third 20 key receiving opening 19. The plates 16 are provided with flanges 117, 118, and 119, surrounding each of the openings 17, 18 and 19 respectively, portions of said flanges being 25 extended through the corresponding slots in the draft sills as best indicated in Figure 2, it being apparent that said flanges provide larger bearing and wearing areas for the respective keys which are received therein.

In the draft rigging as shown, is included a standard coupler indicated broadly by the reference character A; a pair of links or side arms B-B; a front follower C; a rear follower D; a friction shock absorbing mechanism indicated conventionally at E; a coupler key 20; a front follower key 21; a rear follower key 22; and a fourth key 23, function of the latter being hereinafter described.

The front and rear followers C and D are supported by the keys 21 and 22, respectively, which are passed through suitable slots in said followers and corresponding slots 121 and 122 in the links. To sustain the shock-absorbing mechanism E, a detachable saddle plate 24 may be employed, the same being detachably bolted to the draft sills and the front follower C may have bosses 25 projecting into the end wall of the friction shell casting to help support the latter.

50 The rear follower-supporting key 22 is normally disposed at the rear end of the slots 19. The front follower key 21 is normally disposed at the forward ends of the slots 18; and the coupler connecting key 20, which extends through the coupler shank, is normally disposed intermediate the ends of the slots 17 55 and somewhat nearer the front ends thereof than the rear ends. The slots 121 in the links are so arranged as to permit the links to move forwardly a short distance relative to the key 21, and the slots 122 permit the links to move rearwardly with respect to the key 22, so that, in buff, load is not transmitted through the links to the key 21 and the links are free 60 to move rearwardly independent of the key 22. In draft, the links are free to move for-

wardly a limited distance relative to the key 21, but move the rear key 22 forwardly in unison therewith. The slots in the links for the key 20 will be so disposed as to move the key 20 and links in unison when the coupler A is pulled outwardly under draft. 70

As will be evident from the drawings, the links B are confined practically to a straight line movement, but lateral play or angling of the coupler A is permitted with reference thereto, due to the slotted key connection between the coupler shank and links and the fact that the links are spaced apart a greater distance than the maximum width of the coupler shank, it being evident that the slot in the coupler shank is somewhat wider than the key 20, so as to permit lateral motion of the coupler with respect thereto. It will also be noted that the keys and slots are so arranged that the movement under buff is considerably greater than that permitted under draft, the illustration indicating an arrangement wherein the buff movement may be approximately five inches and the draft about two or two and one-half inches.

In carrying out my invention, the links B are straight for the greater part of their length, that is, from points in line with the coupler key 20 to the rear end. Forwardly of the coupler key 20, each link B is provided with an extension 26, inclined downwardly and provided at the front end thereof with a key-receiving opening 27. The supporting key 23 is detachably received within the openings 27, the vertical height of the latter being greater than the thickness of the key and of the turned ends thereof, so as to permit insertion or removal of the key 23 as indicated in Figure 3. The extended portions 26 are of such length and the location of the key 23 is such that the key provides a support for the coupler shank at a point closely adjacent the coupler head, as clearly illustrated in Figure 1, and when the weight of the shank is on the key 23, the latter will be prevented from coming out laterally on account of the turned ends 123 thereof, shown in Figure 3.

In the arrangement which I have shown, it will be observed that no carry iron of usual character is employed or necessary, and preferably the draft sills will be suitably cut away as indicated at 110, to accommodate movements of the key 23. With the parts in the normal or full release position as shown in the drawings, it will be observed that in all positions of the parts the coupler is supported closely adjacent the head thereof by the key 23 at a point forwardly of the coupler key 20, whereby the weight of the coupler head is overbalanced by the combined weight of the links rearwardly of the key 20 and the followers, and to some extent also by the shock absorbing device proper. Hence, as the links are supported at three spaced points by the keys 20, 21 and 22, and the forwardly extend- 115 120 125 130 135 140

ed portions sustaining the coupler shank are rigid with the links, and the key 23 directly supports the coupler shank, it is evident that all tendency of the coupler to drop or sag or 5 fulcrum about the coupler key 20, is prevented and the coupler head of the coupler shank is maintained in its proper horizontal position in axial alignment with the followers and shock absorbing means. Furthermore, 10 the coupler key 20 is relieved of the usual twisting or torsional strain thereon since the coupler is supported forwardly thereof by the key 23.

With my arrangement as shown and de- 15 scribed, it is evident that a constant axial alignment of the coupler shank and shock absorbing device is at all times maintained in all operative positions of the parts whereby the construction is particularly adapted for 20 draft riggings having long travel. It is manifest that the improvements which I have shown do not appreciably add to the cost of manufacture.

I have herein shown and described what I 25 now consider the preferred manner of carrying out my invention, but the same is by way of illustration only and not by way of limitation. All changes and modifications are con- 30 templated that come within the scope of the claims appended hereto.

I claim:

1. As an article of manufacture, a link 35 for railway draft riggings, said link having a key-receiving opening forwardly of its center and provided with a portion project- 40 ing forwardly from said opening, said portion having also a key-receiving opening so located that a key therein will be disposed on the underside of the coupler shank and closely adjacent the head of the coupler.

2. In a railway draft rigging, the combi- 45 nation with draft sills having slotted cheek plates secured thereto; of a coupler; front and rear followers adapted to receive a shock absorbing device therebetween; a pair of 50 side links; a coupler key connecting the shank of the coupler and links and extended through some of the slots of said plates; keys ex- 55 tended through said followers and links and other slots of said plates; and means on said links disposed forwardly of the coupler key for sustaining the weight of the coupler at a point forwardly of said coupler key.

3. In a draft rigging for railway cars, the 55 combination with a coupler; of yoke-acting links adapted to be connected to said coupler by a coupler key, said links being ex- 60 tended forwardly of the coupler key connec- 65 tion; and means extending between said forwardly extended portions of the links for sustaining the shank of the coupler at a point forwardly of the coupler key connection, said means comprising a transversely extend- 70 ing key detachably connected to said links

and disposed beneath the shank of the coupler.

4. In a railway draft rigging, the combi- 75 nation with sills; of a coupler; a shock absorbing device between said sills, having a compression stroke in buff, approximating double the compression stroke of present standard draft gears; front and rear stop-acting means on said sills; and combined aligning and draft means connected to the 80 coupler, said means including side arms op- eratively associated with said shock absorbing device, said means being movable with the coupler in draft, and said arms having means thereon engageable with the coupler shank forwardly of the coupler connection to 85 maintain alignment of the coupler.

5. In a draft rigging for railway cars, the combination with a coupler; of yoke means including side arms having forwardly ex- 90 tends portions forming spaced walls be- 95 tween which the shank of the coupler is accommodated; a key extending through said side walls and coupler for connecting the lat- 100 ter to the yoke means, said side walls being extended forwardly of said keyed connec- 105 tion; and a supporting member connecting said side walls and engaging underneath and slidably supporting the shank of the coupler forwardly of the keyed connection there- 110 of with the yoke.

In witness that I claim the foregoing I have hereunto subscribed my name this 3rd day of December, 1927.
